BASKETBALL REPLICA CANDLE

James E. Eker, 1715 18th St., Woodward, Okla. 73801

Filed Feb. 19, 1974, Ser. No. 443,239

Term of patent 3½ years

Int. Cl. D26—01

U.S. Cl. D73—1 B

FIG. 1 is a right side elevational view of a basketball replica candle showing my new design;

FIG. 2 is a left side elevational view of the basketball replica candle design of FIG. 1;

FIG. 3 is a front elevational view of the basketball replica candle design of FIG. 1;

FIG. 4 is a rear elevational view of the basketball replica candle design of FIG. 1;

FIG. 5 is a top plan view of the basketball replica candle design of FIG. 1; and

FIG. 6 is a bottom plan view of the basketball replica candle design of FIG. 1.

I claim:

The ornamental design for a basketball replica candle, substantially as shown and described.
